UNITED STATES PATENT OFFICE.

WILLIAM PETER NEWKIRK, OF PORTSMOUTH, OHIO, ASSIGNOR OF ONE-FOURTH TO
CHARLES L. BROOKS, ONE-EIGHTH TO WASHINGTON D. ISGRIG, AND ONE-EIGHTH
TO JAMES B. CAMPBELL, ALL OF PUEBLO, COLORADO.

DERAILING DEVICE.

1,198,866.

Specification of Letters Patent. Patented Sept. 19, 1916.

Application filed May 12, 1916. Serial No. 97,114.

To all whom it may concern:

Be it known that I, WILLIAM P. NEWKIRK, a citizen of the United States, and a resident of Portsmouth, in the county of Scioto 5 and State of Ohio, have invented a new and useful Improvement in Derailing Devices, of which the following is a specification.

My invention is an improvement in derailing devices, and has for its object to provide a device of the character specified 10 intended for the use of inspectors, repairmen, and the like, and capable of quick attachment to and detachment from the rail, wherein a plate is provided to be seated on 15 the tread of the rail, and having depending flanges at each side edge for engaging opposite sides of the ball or tread of the rail, and having at one end of each flange a downward extension, extending below the under 20 surface of the tread, the said flanges being at opposite sides and opposite ends of the plate and spaced apart from each other a sufficient distance to permit the derailer to be seated on the rail with the flanges 25 engaging the rail when the plate is transverse to the rail, each extension having an inwardly extending rib at its lower end for engaging the web of the rail when the plate is turned into register with the rail, the said 30 ribs being inclined upwardly toward their inner ends, and key blocks fitting between the ribs and the under surface of the ball or tread to lock the plate in place.

In the drawings:—Figure 1 is a top plan view of the improved derailing device, Fig. 2 is a side view looking at one side, Fig. 3 is a similar view looking at the other side, Fig. 4 is a front view with the rail in section, Fig. 5 is a front view showing the manner of placing the device on the rail, and Figs. 6 and 7 are perspective views of the key blocks.

The present embodiment of the invention is shown in connection with a rail 1, the rail 45 being supported by the usual ties 2, and the device comprises a plate or block 3 of suitable length, having its ends inclined or beveled as shown, and having intermediate its ends an inclined rib 4 for engaging the flange of a wheel to constrain the said flange to pass across the rail to derail the wheel. As shown more particularly in Fig. 1, this rib 4 extends beyond one side of the plate, that is, beyond that side which will be at

the inner side of the rail, and a groove 5' 55 is provided on the outer side of the rib, that is, between the rib and the plate 3 for receiving the flange and gradually lifting it to the top of the plate.

The plate is provided at opposite side 60 edges with depending flanges 5 and 6 of a length to extend to the under surface of the ball or tread of the rail when the derailer is in place on the rail as shown in Fig. 2. These flanges engage the opposite sides of 65 the ball or tread when the derailer is in place, and each flange is provided at one end with an extension 7 and 8, respectively, the said extensions being of a length to extend well below the ball or tread as shown. Each 70 extension is provided at its lower edge with an inturned rib or web 9 and 10, respectively, of a width to engage the web of the rail when the derailer is properly seated, and these webs are inclined with respect to 75 the horizontal and in opposite directions, both inclining upwardly toward their inner or adjacent ends. The extension 8 is provided at its opposite ends with vertical reinforcing ribs 11, the said ribs extending 80 from the rib or web 9 to the upper surface of the plate as shown.

A key block is provided for each extension, and adapted to be arranged between the web or rib and the under surface of the 85 ball or tread, and the said blocks 12 and 13 as shown in Figs. 6 and 7 are wedge-shaped, that is, each block has one edge inclined at the same angle as the inclination of the webs 9 and 10, and the opposite edge is roughened or corrugated as shown and is adapted 90 to engage the under surface of the tread of the rail. These key blocks 12 and 13 are seated on the webs 10 and 9, respectively, and it will be evident that when the device 95 is placed on the rail as shown in Fig. 5 and is turned into the position of Fig. 4 and the key blocks are inserted as indicated in Figs. 2, 3 and 4 the derailer will be firmly locked upon the rail against twisting or lateral 100 movement in either direction. Each key block as shown is of I-shape in cross-section, and the block 13 has a longitudinally extending arm 14, formed by a bar which has one end offset into contact with the body of 105 the key block at the large end thereof and secured thereto as shown, and the body of the bar extends in parallel spaced relation

with respect to the body of the block. This arm is adapted to engage openings 15 in the reinforcing ribs 11 and the free end of the arm is provided with a series of openings 16 for receiving a pad lock 17, or the like, to hold the key block in place.

- A flexible member 18, as for instance, a chain or the like, is secured to a laterally extending lug 19 on the key block 12 at the 10 large end thereof, and this chain is adapted to engage a hook 20 on the extension 7 at the inner end of the said extension to hold the key block in place, and a coil spring 21 is interposed in the length of the chain. 15 When the spring is placed under tension before a link of the chain is engaged with the hook 20 the key block will be firmly held against any possibility of jarring loose. A second chain 22 may be used for anchoring 20 the device to the rail against sliding movement longitudinally thereof. This chain has one end connected to the hook 20 and the other is provided with a hook 23, which is adapted to engage the opposite edge of the 25 base flange of the rail when the chain is passed downwardly below the rail as shown more particularly in Fig. 4.

- A socket 24 is provided intermediate the ends of the plate and near the side adjacent 30 to the flange 5, for receiving the end of a signal staff 25. This staff is provided at its upper end with a signal 26, the said signal in the present instance, being a ring with the legend "Safety first" and the ring is 35 provided with a hook 27 at its upper side for engagement by the bail or handle of a lantern for use at night. A series of indicating plates 28 is pivoted to the upper end of the staff below the ring, and these plates 40 bear legends as for instance "Inspectors", "Repairmen", "Air brakes" and "Private." Preferably the plates are arranged to be held in the extended position shown in Fig. 4 by means of thumb screws or the like, 45 or they are dropped into inoperative position in register with the staff.

In use, the device is especially intended as a warning and derailing device to prevent injury to inspectors, repairmen and the 50 like. The device is placed on the track by arranging the plate 3 transversely of the rail as shown in Fig. 5, and with the lower edges of the flanges 5 and 6 resting on the ball or tread of the rail and with the 55 tensions 7 and 8, depending on opposite sides of the ball or tread. The device is then turned into parallelism with the rail and the flanges 5 and 6 drop down on opposite sides of the ball or tread and with the 60 extensions 7 and 8 below the ball or tread and with the webs 9 and 10 in contact with the web of the rail. The key blocks 12 and 13 are then placed, the block 12 being locked by the chain 21 and the block 13 by the pad 65 lock 17.

The staff 25 with its signals will warn trainmen coming in on the track in use, and if they neglect the warning the train will be derailed, thus absolutely preventing injury to the employees. The plates 28 70 indicate to all concerned the character of work in progress, and as each employee completes his particular labor he will drop the plate 28 pertaining to such labor.

I claim:—

1. A derailer comprising a plate adapted to seat on the tread of a rail and having an inclined deflecting rib, said plate having at opposite side edges depending flanges for engaging opposite sides of the tread of the 80 rail and of a depth to extend to the under side of the tread, each flange having at one end a depending extension and the said extensions being at opposite sides and at opposite ends of the rail and spaced apart 85 at their adjacent ends to receive the tread of the rail between them when the plate is transverse to the rail, each extension having an inturned web at its lower edge for engaging the web of the rail, said webs inclining upwardly toward their adjacent ends and wedge-shaped key blocks fitting between the web of the rail and the flange webs for locking the plate in place, each block having means for preventing disengagement thereof from the derailer. 90

2. A derailer comprising a plate adapted to seat on the tread of a rail and having an inclined deflecting rib, said plate having at opposite side edges depending flanges 10 for engaging opposite sides of the tread of the rail and of a depth to extend to the under side of the tread, each flange having at one end a depending extension and the said extensions being at opposite sides and at opposite ends of the rail and spaced apart 10 at their adjacent ends to receive the tread of the rail between them when the plate is transverse to the rail, each extension having an inturned web at its lower edge for engaging the web of the rail, said webs inclining upwardly toward their adjacent ends, and wedge-shaped key blocks fitting between the web of the rail and the said webs for locking the plate in place. 11

3. A derailer comprising a plate adapted to seat on the tread of a rail and having an inclined deflecting rib, said plate having at opposite side edges depending flanges for engaging opposite sides of the tread of the rail and of a depth to extend to the under side of the tread, each flange having at one end a depending extension and the said extensions being at opposite sides and at opposite ends of the rail and spaced apart 12 at their adjacent ends to receive the tread of the rail between them when the plate is transverse to the rail. 12

4. A derailer having flanges at opposite sides thereof depending on opposite sides 13

of the tread of the rail to the underside thereof, each flange having an extension and the extensions being at opposite ends of the derailer, and spaced apart to engage opposite sides of the tread when the derailer is transverse to the rail, each extension having an inclined web abutting at its free edge the web of the rail when the derailer is in place, and key blocks adapted to fit between the webs and the tread of the rail to hold the derailer in place.

5. A derailer having flanges at opposite

sides thereof depending on opposite sides of the tread of the rail to the underside thereof, each flange having an extension 15 and the extensions being at opposite ends of the derailer, and spaced apart to engage opposite sides of the tread when the derailer is transverse to the rail, each extension having an inclined web abutting at its 20 free edge the web of the rail when the derailer is in place, and means for holding the derailer in place on the rail.
